UNITED STATES PATENT OFFICE.

WILLIAM PUTZKE, OF NORTH MILWAUKEE, WISCONSIN, ASSIGNOR TO EVEREDY AUTO JACK CO., OF MILWAUKEE, WISCONSIN, A CORPORATION.

JACK.

Application filed December 5, 1921. Serial No. 519,847.

To all whom it may concern:

Be it known that I, WILLIAM PUTZKE, a citizen of the United States, residing at North Milwaukee, county of Milwaukee, 5 and State of Wisconsin, have invented new and useful Improvements in Jacks, of which the following is a specification.

This invention relates to automobile jacks.

It is well known that automobile jacks, 10 as heretofore constructed, are very easily lost and are, therefore, not at all times immediately available. It is also difficult to so position the jack in the tool kit, or other receptacle, that it will not rattle. In fact, 15 no means are provided for securing the jack in stored position.

This invention is designed to overcome the above noted defects and, therefore, objects of this invention are to provide a permanently positioned jack for automobiles; 20 to provide a jack which is at all times associated with its corresponding wheel; and to provide a jack which may be readily and instantly brought into use.

25 Further objects are to provide a jack which may be permanently secured to an automobile; which may be locked in inoperative position; and which cannot slip along the axle of the car.

30 Further objects are to provide a jack which is of extremely simple formation; which does not detract from the general appearance of the car to which it is attached; and which may be readily and cheaply manufactured.

An embodiment of the invention is shown in the accompanying drawings, in which:—

Figure 1 is a view of the rear axle of 40 an automobile with a pair of jacks attached thereto.

Figure 2 is a view of one of the jacks in extended or operative position.

Figure 3 is a detail of the means for retaining the jack in inoperative position and 45 shows such means clamped upon the housing.

Figure 4 is a view of the jack, partly in section, and upon an enlarged scale, showing the clamping means for securing the pivotally mounted end of the jack in extended or open position.

Figure 5 is an enlarged view corresponding to Figure 3.

Figure 6 illustrates a modified detail.

50 The jack comprises a main clamping member composed of a pair of jaws 1 and 2,

pivotally joined at 3, and provided with lugs 4 and 5 adapted to be drawn towards each other after the clamp has been positioned about the axle or housing 6. A convenient way of securing the firm clamping 60 action is to pass a bolt 7 thru the apertures 8 and 9 in these lugs and to tighten such bolt to thereby draw the clamp into firm engagement with the housing, or axle, 6. A bracket 10 is secured by means of a 65 rivet 11 to the lower portion of the clamp, preferably to the relatively stationary jaw 1. This bracket is provided with a pair of parallel jaws 12 between which an operating handle or lifting member 13 is pivotally 70 secured by means of a bolt 14. This handle is preferably composed of strap metal formed to provide substantially parallel arm portions resiliently connected by a rounded manipulating end 15. The bottom portion 75 or fulcrum member of the jack is formed of strap iron and comprises a pair of upwardly-extending, parallel arms or standards 16 resiliently joined adjacent their lower ends by means of an arch-shaped member 80 17 and converging adjacent their upper ends to produce parallel spaced portions 18. These spaced portions 18 are positioned upon opposite sides of the handle or lever 13 and pivotally joined thereto by means 85 of a fulcrum bolt 19.

When the jack is not in use, it is bolted in inoperative position by swinging the lever 13 about the pivot bolt 14 and swinging the supporting member 16 into a plane, including the lever 13. When the parts approach the position shown on the left hand side of Figure 1, they are so guided that the inner arm 20 and the outer arm 21 of clamp or hanger 22 pass, respectively, 90 within the rounded portion 15 and externally of the portions 16 of the members. The arms 20 and 21 of this clamp which are offset from a perpendicular plane passing through the axis of the housing 6 are 100 then drawn together by means of a thumb nut 23 carried upon a bolt 24 pivotally mounted at 25 upon the arm 20. A slot is formed in the arm 21 so as to permit the free upward swing of the bolt 24 when it 105 is desired to lock the jack in inoperative position. The clamp or hanger 22 is held upon the housing 6 by means of a bolt 26 which normally draws the parts of the clamp into intimate or binding contact with such 110

housing. The positioning of the various parts of the device is such that when the thumb nut 23 is screwed downwardly upon its bolt 24, the arms 20 and 21 will bind 5 against the two movable portions of the jack and will effectually prevent any rattling or relative motion.

When it is desired to use any one of the jacks, its thumb nut is loosened and the 10 bolt 24 swung downwardly, thereby permitting the parts of the jack to be rocked into the position shown on the right hand side of Figure 1. When the parts arrive in this position, the handle 13 is depressed, 15 thereby lifting the corresponding portion of the car upwardly by a toggle action. This downward motion of the lever 13 is continued until the lever is in line with the portions 16 of the supporting lever or member.

It will thus be seen that an automobile jack has been provided which is of extremely simple construction, of light weight, and which may be readily and cheaply 25 manufactured. It will also be seen that a jack has been provided as a permanent part of an automobile, and has been so designed and positioned that it does not disfigure the car or detract from its general or pleasing 30 appearance. It will also be seen that the jacks will be securely retained in inoperative position and will not rattle or otherwise cause disturbance by dropping downwardly.

35 In Figure 6 the operating handle 13^a is illustrated as having arm portions conforming generally to the contour of the bottom portion of the jack, and a stop 28^a is employed to prevent the handle from pushing thru the base. A cross rod 28 is shown in Figure 4 for the same purpose.

In Figure 6 also coil springs 30 are employed on the bolt 19^a to maintain a clamping pressure between the arms 16 of the 45 base and the lever arm, or shank. These springs also serve to prevent excessive friction, or binding pressure, such as might result if the nut on the bolt 19, shown in Figure 4 were turned up too tightly. In 50 the form disclosed in Figure 6, the parts preferably comprise castings.

I claim:—

1. A hanger for a type of vehicle jack in 55 which a standard element and a lifting member may be nested in close proximity at one side of the center of the jack, said hanger comprising a clamp for attachment to a vehicle axle and having a pair of spaced 60 depending arms offset from a vertical plane passing through the axis of the axle whereby to be positioned to receive the nested and closely adjacent standard element and lifting member of such a jack, together with 65 detent means connected with the hanger

arms and adapted to support therefrom the 65 portions of such a jack received therebetween.

2. In a jack for attachment to a vehicle axle, the combination with a fulcrum member having a pair of spaced standards of 70 a lifting lever pivotally supported from the upper ends of said standards, and resilient means for maintaining said standards in frictional contact with said lifting lever, whereby to prevent rattling of the jack when 75 said jack is attached to a vehicle axle.

3. In a jack for attachment to a vehicle axle, the combination with a fulcrum member having a pair of spaced standards, of 80 a lifting lever, a pivot pin extending through said lifting lever and standards, a spring on said pin engageable with one of said standards, and means on said pin engageable with said spring and the other of said standards, whereby to maintain said 85 standards in frictional contact with said lever.

4. A hanger for vehicle jacks, said hanger comprising an axle-encircling portion terminating in substantially parallel arms one 90 of which is substantially tangential and the other of which is substantially radial with respect to said portion, a clamping bolt connecting said arms adjacent said axle-encircling portion and adapted to clamp said 95 portion to an axle, and a second clamping device spaced from the bolt along said arms and adapted to compress the extremities of said arms about interposed portions of a jack.

5. In a jack for attachment to a vehicle axle, the combination with a fulcrum member having a pair of spaced resiliently connected standards, of a lifting lever, a pivot pin extending through said lifting lever 100 and standards, said pivot pin having spring means engaging said standards thereby to cause said standards to frictionally engage said lever.

6. A hanger for vehicle jacks, said hanger comprising an axle-encircling portion terminating in substantially parallel arms one of which is substantially tangential and the other of which is substantially radial with respect to said portion, a clamping bolt connecting said arms adjacent said axle-encircling portion and adapted to clamp said portion to an axle, and a second clamping device spaced from the bolt along said arms and adapted to compress the extremities of 110 said arms about interposed portions of a jack, said clamping device comprising a bolt in pivotal connection with one of said arms and the other of said arms being provided with a slot to receive said last mentioned 115 bolt.

WILLIAM PUTZKE,
